W. N. Clark,

Steering.

No 68,413

Patented Sept. 3, 1867.

United States Patent Office.

WILLIAM N. CLARK, OF CHESTER, CONNECTICUT, ASSIGNOR TO HIMSELF AND JAMES B. CLARK, OF THE SAME PLACE, AND WILLIAM N. CLARK ASSIGNS ONE HALF HIS RIGHT TO HENRY PEMBER.

Letters Patent No. 68,413, dated September 3, 1867.

IMPROVED MEANS FOR HANGING RUDDERS.

The Schedule referred to in these Letters Patent and making part of the same.

TO ALL WHOM IT MAY CONCERN:

Be it known that I, WILLIAM N. CLARK, of Chester, in the county of Middlesex, in the State of Connecticut, have invented a new and improved Mode of Hanging the Rudder of Boats and Vessels; and I do hereby declare that the following is a full and exact description thereof, reference being had to the accompanying drawings, and to the letters of reference marked thereon.

The nature of my invention consists in providing the stern of a boat or vessel with a metal plate, having a groove enlarged inwardly, which groove is to receive a corresponding tongue, to which the rudder is permanently hinged, thereby hanging the rudder; and also in providing the tongue with extensions for hanging a balance rudder.

To enable others skilled in the art to make and use my invention, I will proceed to describe its construction and operation.

In place of the devices now used for hanging rudders I attach a metal plate having a dove-tailed groove, or a groove enlarged inwardly, into which groove I fit a corresponding metal tongue, to which the rudder is permanently attached by any suitable hinge.

Figure 1, of the accompanying drawings, is the representation of a rudder hung according to my invention. B represents the stern of a boat to which a metal plate, P, having a dove-tailed groove, g, is represented as attached by screws passing through the extensions in the plate, represented at e e e in Figure 2, which is a representation of the plate detached. T represents a tongue, dove-tailed to correspond with the groove g in the plate, and provided with strap-eyes, shown at S S S S, through which the straps a a pass, and are attached to the rudder R, permanently hinging the rudder to the tongue, whereby it follows that to "unship the rudder," the tongue must be withdrawn from the groove in the plate upwardly, the groove being slightly enlarged upwardly, as shown, and shipped by the reverse process. I insert a pin in the tongue near the top, which enters the recess i provided for it in the top of the plate, and fixes or limits the distance the tongue may enter. The pin is marked o in Figure 3, which is a representation of the tongue detached. Figure 4 is the representation of the tongue provided with extensions for a balance rudder, which are marked n n. The extensions upon the tongue, by being carried out, will enable the rudder to be hung in the centre to balance it, if desired. When the head of the rudder to be hung ships through a rudder port, of course the tongue cannot wholly be entered from the top of the groove; in that case, instead of making the corresponding enlargement or dove-tail of the tongue continuous, I make it in sections, and construct the plate with corresponding ports or openings to receive them, from which the dove-tailed sections enter their corresponding grooves in the plate instead of being passed in from the top of the groove.

With the arrangement heretofore known and used for hanging rudders it has been more or less difficult to readily ship the rudder of a small boat, in consequence of one of the hinges being below the surface of the water. This makes it difficult to effect the connection of the hinges when the water is rippled or not clear, and especially difficult in the night, when the waves are striking against the rudder, and the connection is not sure in rough weather, while the liability of the rudder to get unhinged by contact with the shore, and by various other causes, makes it necessary that it should be unshipped when not in use. By my improved mode of hanging, the rudder may be readily shipped under all circumstances, and is securely hung.

What I claim as my invention, and desire to secure by Letters Patent, is—

The plate P and tongue T, in combination with the hinged rudder R, substantially as herein described and for the purpose specified.

WILLIAM N. CLARK.
